Int. Cl. D6—01
U.S. Cl. D33—14

Fig. 1

Fig. 2

Fig. 3

Fig. 4

FIG. 1 is a perspective view of a teaching table showing my new design;

FIG. 2 is a front elevational view thereof;

FIG. 3 is a rear elevational view thereof; and

FIG. 4 is a top plan view thereof.

The broken line showing in FIGS. 1, 2 and 3 is for illustrative purposes only.

The essential features of my design reside in those portions shown in full lines on the drawing.

This application is a divisional application of my co-pending application, Ser. No. D. 2,251, filed May 11, 1966, which issued as Patent D. 209,911, Jan. 16, 1968.

I claim:

The ornamental design for a teaching table, substantially as shown and described.
